(57) **CLAIM**

The ornamental design for a bell for bicycles as shown and described.

DESCRIPTION

FIG. 1 is a top perspective view of a bell for bicycles, in accordance with our new design;

FIG. 2 is a front view thereof;

FIG. 3 is a rear view thereof;

FIG. 4 is a left side view thereof, the right side view being a mirror image of the left side view;

FIG. 5 is a top view thereof; and,

FIG. 6 is an exploded view of FIG. 1.

The broken lines in the figures show portions of the bell for bicycles that form no part of the claimed design.
